UNITED STATES PATENT OFFICE

EL ROY L. PAYNE, OF LOS ANGELES, CALIFORNIA, ASSIGNEE TO GAS FURNACE
CONTROL CO., A CORPORATION OF CALIFORNIA

ELECTRICALLY-OPERATED VALVE

Application filed March 26, 1924. Serial No. 702,018.

This invention relates to electrically operated valves, and particularly to a valve actuating mechanism adapted to be operated or controlled from a point remote from its location, to either turn on or off or to position to pass gas in a quantity or quantities less than its full capacity.

The present case covers improvements in my electrically operated valve mechanism shown and described in a co-pending application filed November 5, 1921, Serial No. 513,204.

While the preferred specific embodiment of my invention—as herein shown and described—has been designed primarily for use in connection with gas heating appliances, it, obviously, need not necessarily be confined to such a limited application, as its principles may be utilized to advantage under many and varied conditions and circumstances where applicable.

My device is characterized by its compactness, durability, simplicity and low cost of manufacture; and also by the novel arrangement and construction of the operating mechanism to effect this end. In this connection, a notable feature of the mechanism I employ is in an arrangement for easily and quickly adjusting the valve opening to vary or regulate the quantity of gas passing through it. A further feature is the combination therewith of a practical arrangement of electrical contacts electrically connected to suitable signal means, to indicate the several positions of the valve at a point remote therefrom.

In the following detailed description of the construction and operation of my valve reference is made to the accompanying drawings, in which the several figures thereof may be briefly described as follows:

Figure 1 is a top plan view of my valve with the cover of its housing removed;

Fig. 2 is a front end elevation, taken as indicated by the line 2—2 of Fig. 1;

Fig. 3 is a longitudinal vertical sectional view taken as indicated by the line 3—3 of Fig. 1, showing the case cover in place;

Fig. 4 is a view similar to Fig. 3 taken on line 4—4 of Fig. 1;

Fig. 5 is a transverse vertical sectional view taken on line 5—5 of Fig. 1;

Fig. 6 is a fragmentary detail view showing the parts, as in Fig. 4, in closed position;

Figs. 7, 8 and 9 are detail views of the switch member carried by the cam shaft;

Fig. 10 is a perspective view of the valve lifting arm;

Fig. 11 is a perspective view of the cam pins carried by the cam shaft; and

Fig. 12 is a wiring diagram illustrating the electrical connections between the valve and signal lights.

While in the present case I include as the essential elements of my valve and its actuating mechanism, the valve itself; an electro-magnet operatively connected by a pawl and ratchet mechanism with the valve member, to successively move it to its several positions to either turn it on or off or pass gas in different quantities; and a system of electrical contacts electrically connected with signal lights, to indicate the position the valve is in, as in my aforementioned co-pending application; the particular valve, the ratchet mechanism and electrical contacts are structurally different from those included in that application, and in this combination and arrangement may be claimed as improvements. To this arrangement I have added my improved type of valve lifting or actuating mechanism, together with certain adjusting elements, whereby I can exactly regulate the valve openings to vary the passage of gas in either full or intermediate quantities, as will best suit the particular case.

Referring now to the drawings the numeral 12 designates the valve casing and 13 a case or housing for inclosing the actuating

50

90

mechanism, to protect the latter from the elements and from dust and dirt. The housing 13 is rigidly mounted upon the valve casing 12, as by means of screws 14; 5 and a cover 15 is provided for it. The top and front sides of the housing are thus left open to permit easy access to the actuating mechanism. Cover 15 may be secured in place in any suitable manner.

- 10 The opposite ends of the valve casing 12 are internally screw-threaded for the reception of the externally screw-threaded ends of fuel feed and discharge pipes 16 and 17, respectively. A central partition 18 divides 15 the valve casing 12; this partition having a central, longitudinally disposed flat portion 19 in which a port 20 is cut. Preferably this port will be conical to form a seat for a preferably cylindrical valve member 21. 20 Fuel passes through the casing 12 and the port 20 from the feed pipe 16 to the discharge pipe 17.

A valve sleeve 22 extends through the bottom 23, of the housing 13, and is rigidly 25 mounted upon the valve casing 12 by its externally screw-threaded lower end seating in an internally screw-threaded bore 24. The bottom end of the sleeve 22 is closed, except for a bore 25 in which the cylindrical 30 valve member 21 is slidably mounted and which forms a guide therefor. The internal bore 26 of the sleeve 22 is somewhat larger in diameter than the valve member 21; the latter having a cylindrical collar 27 which 35 has a sliding fit therein. A helical, expansive spring 28 surrounds the valve stem 29 and is confined between the collar 27 and a closure plate 30 on the top of the sleeve 22. The plate 30 may be secured in place by 40 screw-threads or have a forced fit in the end of the sleeve. The spring 28 acts to normally hold the valve member 21 seated in the port 20.

By making the port 20 tapered or conical 45 and the valve member 21 cylindrical, wear on the latter will be automatically taken up and it will always form a gas tight fit on its seat.

The valve stem 29 extends loosely through 50 a bore in the closure plate 30 and continues somewhat above the upper end of the sleeve 22. A cam lever 31 is secured at one end to a transversely extending shaft 32, revolvably journaled in suitable bearing bores in 55 the opposite side walls 33 of the housing 13. This mounting permits vertical oscillation of the lever 31, in a plane parallel to the axis of the valve member 21 and its stem 29.

An aperture 34, slightly larger in diameter 60 than the stem 29, is cut in the lever 31 into which the stem 29 may extend. An adjustment screw 35 is carried by the upper end of the stem 29, and a collar 36 is carried thereon, intermediate its end and the 65 top face of the lever 31, to bridge the aper-

ture 34. This provides a lifting connection between the lever 31 and valve stem 29, yet allows the lever to be depressed below the plane of the upper end of the stem 29. The object of this is so that when the valve member 21 is seated in the port 20, by the action of the spring 28, it will not operate to hold the lever 31 upwardly, but will permit the latter to drop its full distance, as shown in Fig. 6. In other words, the connection between the stem 29 and lever 31 is only a lifting connection, so that any wear upon the valve member 21 or port 20 will be compensated for by this loose connection and the action of spring 28, and will always seat properly, to make a gas tight connection, without any limitation imposed by a rigid connection with the lever 31.

A shaft 37 extends across the housing 13 and is revolvably journaled at each end in suitable bearing bores in the sides 33. This shaft carries a collar 38, rigidly mounted thereon, in which a plurality of radially disposed cam pins 39-39^a, 40-40^a and 41-41^a are rigidly secured. I term these pins "cam pins" because they are, in effect, cams, which successively engage the outer end of the lever 31 to raise it and consequently lift the valve member 21 against the action of the spring 28. While I have here shown these cams to be in the form of pins, which is a simple and durable construction, any suitable form of cam may be utilized for this purpose.

The pins 39 and 39^a, which are mounted in the collar 38 in circumferential alinement and diametrically opposed relation, are the shortest, and are positioned to successively engage, upon rotation of the shaft 37, the under surface of a flexible contact plate 42 on the under side of the lever 31. These short cam pins 39 and 39^a—which are both of the same length—are adapted to lift the valve member 21 from its seat, through the medium of the lever 31, one-third of its full opening. The cam pins 40 and 40^a, which are likewise of the same length and mounted in diametrically opposed relation, are slightly longer than the pins 39 and 39^a and are adapted to engage the under face 100 of a flexible contact plate 43 also secured to the under side of the lever 31. Pins 40 and 40^a are adapted to raise the valve member two-thirds of its full distance, through the medium of the lever 31. Cam pins 41 and 41^a, are also of equal length and mounted in diametrically opposed relation, and are adapted to engage the under face 105 of a contact finger 44 on the lever 31. Pins 41 and 41^a operate to raise the valve member 21 its full distance to open the valve to its full capacity. Shaft 37 is adapted 110 to be rotated in the direction indicated by the arrows in the several figures, consequently the pins 41, 40 and 39 will engage 115

120

125

130

their respective contact surfaces on the lever 31 in inverse numerical order (although this order may be reversed) so that the valve member 21 will be first opened its full distance by the pin 41, to pass gas to its full capacity, and thence by the successive engagement of the pins 40 and 39 with their respective contact plates on the lever 31, the valve member will be closed, by the action of spring 28, first to two-thirds, and thence to one-third capacity, and thence entirely closed when the outer end of the lever 31 rests upon the collar 38 intermediate the pins 39 and 41^a or 39^a and 41, as shown in Fig. 6. As will be more fully hereinafter described, the shaft 37 is to be intermittently rotated in steps of one-eighth of a revolution and consequently the valve will be open to its full capacity, thence closed to two-thirds and one-third its capacity, thence entirely closed, twice during each revolution of the shaft 37.

The contact plates 42 and 43 are preferably formed of a light spring metal and are rigidly secured at their inner ends, by any suitable means, to the under face of the lever 31. Normally these members will lie flat against the under face of the lever and their outer ends are adapted to be adjustably held in spaced relation thereto by means of adjusting screws 42^a and 43^a, respectively. By this means the intermediate openings of the valve member 21 may be exactly adjusted to pass gas in desired quantities, without change or alteration of the length of the cam pins. While I have here shown the use of the contact plates 42 and 43 to adjust only the intermediate openings of the valve, it is nevertheless clear that such adjustable means may be easily used in connection with the cam pins 41 and 41^a to also regulate the opening of the valve to its full capacity.

The shaft 37 is adapted to be intermittently rotated by means of an electro-magnet 45, which is in the form of a solenoid. This may be secured within the housing 13 by means of a screw 46 extending through the rear wall 47 thereof. This magnet has a core 48 slidably mounted therein, in the usual manner, to the outer end of which a hook pawl 49 is pivotally secured by means of a pivot pin 50. A ratchet wheel 51 is rigidly mounted upon the shaft 37 in alignment with the core 48 and pawl 49. Specifically this ratchet wheel has an annular channel 52 cut therein across which a plurality of pins 53 extend and which are adapted to be successively engaged by the hook shoulder 54 upon the pawl 49. There are eight of the pins 53 spaced equidistant around the ratchet wheel 51 so there will be eight intermittent movements for each revolution of the shaft 37, each one of these being effected by a distinct energization of the magnet 45. The pins 53 are spaced inwardly from the

perimeter of the wheel 51 so the pawl 49 will always ride in the annular channel 52 during its backward and forward movements.

A contractile helical spring 55 is secured at one end to a lug 56, on the bottom edge of the pawl 49, and at its opposite end to a pin 57 in the bottom 23 of the housing 13, which normally holds the pawl 49 upwardly against the pins 53 and the core 48 outwardly in position to rotate the shaft 37 one step upon energization of the magnet 45, (see Fig. 3). An arcuate upper edge 58, just back of the shoulder 54, is adapted to engage the lower pins 53, as shown in Fig. 3, when the pawl 49 is in its normal inoperative position, leaving the shoulder 54 forward of the adjacent pin 53. The forward upper edge 59 of the pawl 49 is inclined downwardly to ride over the intermediate pins 53 during forward movement of the pawl, after it has rotated the shaft 37 one step by energization of the magnet 45.

The shaft 37 may be manually rotated by means of an actuating pin 60, secured at its inner end to the core 48 by means of the pivot pin 50 and mounted longitudinally slidably in a bracket 61 secured to the adjacent side 33 of the housing 13. The outer end of the pin 60 extends through the forward wall of the cover 15 in convenient position for manual actuation. The outer end of the core 48 abutting against the inner end of the bracket 61 forms a stop to limit its forward movement and to stop the pawl 49 in position to engage the next successive pin 53, as shown in Fig. 3.

In Fig. 12 I have shown a wiring diagram including a system of electrical signals for indicating the position the valve is in, but before describing this system I will first describe the arrangement of electrical contacts and connections in conjunction with the valve actuating mechanism.

A block 62 of any suitable insulating material, preferably cylindrical in configuration, is rigidly mounted upon the shaft 37. This block has a plurality of annular channels, 63, 64 and 65 suitably spaced by intermediate walls of the material. A plurality of resilient electrical contact fingers 66, 67 and 68 are each rigidly secured at one end to the inner end extensions of complementary binding posts 69, 70 and 71; the latter all being suitably insulated from the housing 13 by extending through a block of insulating material 72, suitably mounted upon the said wall 33 of the housing 13. The free ends of fingers 66, 67 and 68 are substantially co-terminous and each yieldingly rides in its respective channel 63, 64 and 65 of the block 62, as shown in Figs. 1 and 2. The block 62, which may be properly termed a "switch block" carries a plurality of switch pins 73, 74, 75 and 73^a, 74^a and 75^a, each spaced apart a distance of one-eighth of a revolution of

the shaft 37, to correspond with the spacing of the cam pins 39, 40 and 41 and pins 53. Like the cam pins 39 and 39^a, 40 and 40^a, and 41 and 41^a, the pins 73 and 73^a, 74 and 74^a, and 75 and 75^a are respectively positioned in diametrically opposed relation, and likewise the pins 75 and 73^a and 73 and 75^a are spaced apart 90° to correspond with the spacing between the cam pins 39 and 41^a and 39^a and 41. The switch pins 73 and 73^a extend across the annular channels 63 and 64 to close the circuit by engagement with the contact fingers 66 and 67; the pins 74 and 74^a extend across channels 64 and 65 to close the circuit by engagement with the fingers 67 and 68; and the pins 75 and 75^a extend across all of the channels 63, 64 and 65 to simultaneously engage all of the contact fingers 66, 67 and 68.

It is to be noted that the switch pins extend continuously across the channels and through their several dividing walls, as clearly shown in Fig. 7, and constitute movable switches to effect circuit closures between the several contact fingers. It is also to be noted that these pins are set inwardly from the perimeter of the switch block 62 so the yielding ends of the contact fingers will always ride in their respective channels and be kept in proper alignment.

Referring now to the wiring diagram of Fig. 12, each of the contact fingers 66, 67 and 68 is connected to a binding post 69, 70 and 71, respectively, by wires 76, 77 and 78. A wire 79 leads from the binding post 70 to one side of a battery B and a wire 80 leads from the opposite side of this battery to a binding post 81, and in which a manually operable closure switch 82 is interposed. A wire 83 connecting with wire 77, and a wire 84 leading from binding post 81 connect with opposite ends of the coil of magnet 45. Thus, upon closure of the switch 82 magnet 45 will be energized to effect rotation of the shaft 37, through the medium of the pawl and ratchet mechanism hereinbefore described. A wire 85 leads from binding post 69 to one side of an incandescent lamp 86 and a wire 87 connects the opposite side of this lamp with wire 80. A wire 88 leads from binding post 71 to one side of another incandescent lamp 89 and a wire 90 connects the opposite side of this lamp with wire 80. As will be more fully hereinafter explained, when both the lights 86 and 89 are de-energized it will indicate that the valve is closed, when the light 86 is energized it will indicate the valve is one-third open, when light 89 is energized it will indicate that the valve is two-thirds open, and when both of these lights are energized it will indicate that the valve is open to its full capacity.

The mode of operation of the device is as follows:

When the mechanism is in its normal in-

operative position, with the valve 21 seated to close the port 20, the several parts are in the position illustrated in Fig. 6; the latter figure illustrating the lever 31 in its lowermost position with its outer end resting upon the collar 38 intermediate either the cam pins 39 and 41^a or 39^a and 41. When in this position the outer ends of the contact fingers 66, 67 and 68 are resting upon the switch block 62 intermediate either the switch pins 75 and 73^a or 73 and 75^a. For clarity of disclosure it may be stated that switch pins 75 and 75^a are in axial alignment with cam pins 41 and 41^a, switch pins 74 and 74^a in axial alignment with cam pins 40 and 40^a and switch pins 73 and 73^a in axial alignment with cam pins 39 and 39^a; so that when each of the respective cam pins is in engagement with its complementary end of the lever 31, to actuate the valve member 21, the corresponding switch pin will be in position to engage and connect the free ends of the proper switch fingers 66, 67 and 68, to indicate, through the medium of the signal lamps 86 and 89, the position the valve is in.

Assuming the several parts to be in the positions above stated, when the valve is closed, closure of the switch 82 will effect energization of the magnet 45, causing its core 48 to be drawn inwardly and the shaft 37 rotated one-eighth of a revolution, through engagement of the pawl 49 with the adjacent pin 53. As soon as the magnet 45 is de-energized by again opening the switch 82, or by any other means, the spring 55 will return the pawl 49 and core 48 forward to the position shown in Fig. 3, the inclined surface 59 riding over the next forward pin. This energization of the magnet will rotate the shaft 37 to the position illustrated in Fig. 4, where the cam pin 41 has engaged its complementary end of the lever 31 and raised the valve 21 to its full open position, against the action of spring 28. This operation effects movement of the complementary switch pin 75 to position to engage the free ends of all of the contact fingers 66, 67 and 68, and which, through the medium of the connecting contacts illuminates both of the lamps 86 and 89, thereby indicating that the valve is in full open position. If it is desired to close the valve to two-thirds its full capacity the switch 82 is again closed, effecting energization of magnet 45 and rotating shaft 37 another one-eighth of a revolution, through the medium of the aforesaid pawl and ratchet mechanism, to a point where the cam pin 40 will be in engagement with its complementary contact plate 43. In this movement the action of spring 28 closes the valve to two-thirds its capacity and the proper switch pin 74 moves to position to connect the free ends of switch fingers 67 and 68, thereby energizing the

lamp 89 to indicate that the valve is two-thirds open. Upon the next closure of the switch 82 the shaft 37 will be similarly rotated one-eighth of a revolution until the 5 cam pin 39 engages its complementary contact plate 42, permitting the spring 28 to move the valve member 21 downwardly to one-third its capacity. This operation effects movement of the switch pin 73 to position 10 to engage and connect the ends of switch fingers 66 and 67 thereby energizing lamp 86 and indicating that the valve is one-third open. The next closure of the switch 82 rotates the shaft 37 one-eighth of a revolution 15 to a point where the lever 31 rests upon the collar 38 intermediate the cam pins, as illustrated in Fig. 6, at which time the spring 28 effects seating of the valve member 21. This operation also rotates the 20 switch block 62 to a point where all of the contact fingers 66, 67 and 68 are resting upon the block intermediate the switch pins, as illustrated in Fig. 1.

While I have shown and described the 25 preferred specific embodiment of my invention, I nevertheless reserve the right to make such changes or modifications in structure as will properly come within the scope of the appended claims. For instance, my mechanism need not be limited to an arrangement to effect any particular number of intermediate openings of the valve, as it may be arranged to open the valve to any number of intermediate points from a single one to 35 several, without departing from the spirit of my invention. Also, while I have arranged this mechanism to effect the short movements by making eight intermittent movements to each revolution of the shaft 40 37, I may either increase or diminish the number of its intermittent movements as will best suit the particular conditions; as well as reverse the order in which the valve is opened and closed.

Having described my invention, I claim: 45 1. In combination, a valve having a stem, yielding means to hold said valve normally closed, a cam lever pivotally mounted adjacent said valve, a loose, adjustable lifting connection between said valve stem and lever for raising the valve against the action of its holding means, a cam wheel adapted to engage said lever to intermittently open the valve or move it to intermediate positions 50 to pass gas in quantity less than its full capacity, and adjusting means to individually vary the extent of each valve movement.

2. In combination, a valve having a stem, yielding means to hold said valve normally 55 closed, a cam lever pivotally mounted adjacent said valve, a loose, adjustable lifting connection between said valve stem and lever for raising the valve against the action of its holding means, a cam wheel adapted to 60 engage said lever to intermittently open the

valve or move it to intermediate positions to pass gas in quantity less than its full capacity, adjusting means in connection with said lever to individually vary the extent of each valve movement, an electro-magnet, and a ratchet mechanism operatively connecting said magnet and cam wheel for intermittently actuating the valve. 70

3. In combination, a valve having a stem, spring means in connection with the valve stem to hold the valve normally closed, a cam lever adapted to engage the valve stem to only actuate it against the action of said spring, cam means adapted to actuate said lever to open the valve to full capacity or to an intermediate position to pass gas in quantity less than its full capacity, and adjusting means in connection with said cam lever to individually adjustably vary the extent of each valve movement. 75

4. In combination, a poppet valve having a stem, yielding means to hold said valve normally closed, a cam lever pivotally mounted adjacent the valve, a loose, adjustable lifting connection between said valve stem and lever for raising the valve against the action of its spring, said connection being arranged to permit downward movement of the lever after the valve is seated, a cam wheel adapted to engage said lever to intermittently open the valve or move it to intermediate position to pass gas in quantity less than its full capacity, adjusting means in connection with said lever to individually vary the extent of the several valve movements, an electro-magnet and a ratchet mechanism operatively connecting said magnet and cam wheel for intermittently actuating the valve. 90

5. In combination, a valve, means to actuate said valve from closed position successively to several definite, predetermined open positions, to pass fluid in different quantities, the movement being from closed position successively to its several open positions and then back to closed position, and adjusting means in connection with the actuating means whereby the extent of the different valve openings may be separately varied. 105

6. In combination, a valve, electro-magnetically operated means to intermittently actuate said valve from closed position successively to several different, predetermined open positions, to pass fluid in different quantities, the movement being from closed position successively to its several open positions and then back to closed position, and adjusting means in connection with the actuating means whereby the extent of the different valve openings may be separately varied. 115

7. In combination, a gate valve, yielding means to normally hold said valve closed, means to actuate said valve from closed posi- 120

tion successively to several definite, predetermined open positions, to pass fluid in different quantities, the movement being from closed position successively to its several open positions and then back to closed position, and adjusting means in connection with the actuating means whereby the extent of the different valve openings may be separately varied.

8. In combination, a gate valve, yielding means to normally hold said valve closed, electro-magnetically actuated means to actuate said valve from closed position successively to several definite, predetermined open positions, to pass fluid in different quantities, the movement being from closed position successively to its several open positions and then back to closed position, and adjusting means in connection with the actuating means whereby the extent of the different valve openings may be separately varied.

9. In combination, a gate valve, a cam actuated mechanism to move said valve from closed position successively to several definite, predetermined open positions, to pass fluid in different quantities, said mechanism being arranged to effect movement from closed position successively to its several open positions and then back to closed position, an electro-magnet, a pawl and ratchet mechanism operatively connecting said electro-magnet and cam mechanism to intermittently move the valve to its several positions, and adjusting means in connection with the actuating means whereby the extent of the different valve openings may be separately varied.

10. In combination, a gate valve, a cam actuated mechanism to move said valve from closed position successively to several definite, predetermined open positions, to pass fluid in different quantities, said means being arranged to effect movement from closed position successively to its several open positions and then back to closed position, an electro-magnet, a pawl and ratchet mechanism operatively connecting said electro-magnet and cam mechanism to intermittently move the valve to its several positions, and adjusting means in connection with the actuating means whereby the extent of the different valve openings may be separately varied.

11. In combination, a gate valve, yielding means to hold said valve normally closed, a cam actuated mechanism to move said valve from closed position successively to several definite, predetermined open positions, to pass fluid in different quantities, a cam actuated mechanism to open said valve or move it to its several open positions, said mechanism being adapted to move the valve from closed position successively to its several open positions and then back to closed

position, an electro-magnet, a pawl and ratchet mechanism operatively connecting said electro-magnet and cam mechanism to intermittently actuate the valve, and adjusting means in connection with the actuating means whereby the extent of the different valve openings may be separately varied.

12. In combination, a gate valve, yielding means to normally hold said valve closed, a cam actuated mechanism to move said valve from closed position successively to several definite, predetermined open positions, to pass fluid in different quantities, said mechanism being adapted to move the valve from closed position successively to its several open positions and then back to closed position, an electro-magnet, a pawl and ratchet mechanism operatively connecting said electro-magnet and cam mechanism to intermittently actuate the valve, and adjusting means in connection with the actuating means whereby the extent of the different valve openings may be separately varied.

13. In combination, a gate valve, a cam lever pivotally mounted adjacent said valve and operatively connected therewith, cam means adapted to engage said lever to move said valve from closed position successively to several definite, predetermined open positions, to pass fluid in different quantities, said means being adapted to move the valve from closed position successively to its several open positions and then back to closed position, an electro-magnet, means operatively connecting said electro-magnet and cam means to intermittently actuate the valve, and adjusting means in connection with the actuating means whereby the extent of the different valve openings may be separately varied.

14. In combination, a gate valve, yielding means to hold said valve normally closed, a cam lever pivotally mounted adjacent said valve and operatively connected therewith, a plurality of cam elements adapted to successively engage said lever to move the valve from closed position successively to several different open positions, to pass fluid in different quantities, said elements being arranged to move the valve from closed position successively to its several open positions and then back to closed position, an electro-magnet, a pawl and ratchet means operatively connecting said magnet and cam means to intermittently actuate the valve, and adjusting means in connection with the actuating means whereby the extent of the different valve openings may be separately varied.

15. In combination, a gate valve, yielding means to hold said valve normally closed, a cam lever pivotally mounted adjacent said valve and operatively connected therewith, a plurality of cam elements adapted to successively engage said lever to move the valve

from closed position successively to its several different open positions, to pass fluid in different quantities, the movement in each case being from closed position successively to its several open positions and back to closed position, an electro-magnet, a pawl and ratchet mechanism operatively connecting said magnet and cam elements to intermittently actuate the valve, and adjusting means in connection with the actuating means whereby the extent of the different valve openings may be separately varied.

In witness that I claim the foregoing I have hereunto subscribed my name this 28th day of February, 1924.
